UNITED STATES PATENT OFFICE.

WILLIAM E. BIHL, OF CHICAGO, ILLINOIS, ASSIGNOR TO IRON MOUNTAIN CO., OF CHICAGO, ILLINOIS, A CORPORATION OF ILLINOIS.

PRESSURE-CONTROLLING MECHANISM.

Application filed May 6, 1925. Serial No. 28,318.

This invention in general pertains to pressure controlling mechanism and more particularly to improvements in valve devices. I have reference more specifically to that type 5 of valve devices, commonly termed "expansion valves", such as those employed to regulate and control the supply of a refrigerant to the expansion coil or chamber in refrigerating apparatus.

10 To those versatile and familiar with the refrigerating art, it is well known that in a refrigerating apparatus the refrigerating medium is supplied to the expansion coils from a receiver containing liquid refrigerant 15 under comparatively high pressure. Ordinarily, the passage of the refrigerant from the liquid receiver to the expansion coil is controlled by a so-called expansion valve through which the refrigerant is permitted 20 to pass in small quantities as it is needed. After the refrigerant has passed through the above mentioned expansion valve, it enters the expansion coil or chamber under a low pressure, wherein it expands so as to 25 cool the air or other medium surrounding the coil, in a manner well known to those skilled in the art. When the refrigerant medium in the expansion coil has expanded to a sufficient degree and has taken up the 30 maximum amount of heat under the involved conditions, it is returned to the liquid receiver as a liquid under high pressure, by a suitable mechanism such as a compressor. It then may pass again to the expansion 35 valve which admits it to the expansion coil as before.

An object of the present invention is to provide an improved pressure controlling device.

40 Another object of the present invention is to provide a simple, compact and inexpensive, but yet strong expansion valve which will efficiently control the flow of the refrigerant to the expansion coils.

45 A further object of the present invention is to provide an expansion valve of such a construction as to facilitate adjustment thereof and which will permit of its being taken apart for cleaning or repair, as the 50 case may be.

In accordance with the general features of the invention, there is provided an expansion valve casing comprising two parts bolted together with a diaphragm therebetween.

Positioned on one side of the diaphragm in 55 one of the parts of the casing is a relatively strong adjustable spring for deflecting the diaphragm. Located on the other side of the diaphragm in the other part of the casing is a weaker adjustable spring for counteracting the pressure of the first spring. Connected to the weaker spring is leverage 60 mechanism for controlling a needle valve in the inlet of the expansion valve proper. Associated with the same part of the casing 65 as the inlet, is an outlet which is adapted to be connected to an expansion coil. When the pressure of the refrigerant in the outlet and in the expansion coil is below a predetermined amount, the total pressure on 70 the diaphragm, on the side of the weaker spring, is slightly less than that exerted on the opposite side of the diaphragm by the larger spring. Consequently, the diaphragm 75 is deflected in the direction of the low pressure thereby compressing the weaker spring, causing the leverage mechanism to open the needle valve in the inlet to allow liquid to enter the outlet and expansion coil. On the other hand, when sufficient refrigerant has 80 entered the outlet and expansion coil to increase the pressure to the previously mentioned predetermined amount, the reverse action takes place closing the needle valve. That is to say, the pressure of the liquid in 85 the valve and expansion coil is then sufficient to move the diaphragm back to its undeflected position, overcoming the pressure exerted by the strong spring. In other words, the valve is really a balanced pressure regulating 90 device.

Other objects and advantages of the present invention will more fully appear from the following detailed description, taken in connection with the accompanying drawings which illustrate one embodiment thereof, and in which

Fig. 1 is an elevation of the improved expansion valve with its cap removed; and

Fig. 2 is a sectional view taken on the 100 line 2-2 of Fig. 1 looking in the direction indicated by the arrows.

Referring now to the drawings in detail in which like reference numerals designate similar parts throughout the several views, 105 10 denotes generally the casing of the improved expansion valve which comprises two parts 11 and 12. Part 12 is preferably

- 2
- in the form of a cap and is adapted to be secured to the part 11 by bolts 13'. A diaphragm 13 preferably made of a thin disc of flexible metal, separates the part 11 from the part 12 and is clamped to the part 11 by the part 12 and the bolts 13'. Intermediate the flange 14 of the part 11 and the diaphragm 13, is a ring-like gasket 15 which may be made of any suitable material.
- 10 The part 12 is equipped with a centrally disposed hub 16 provided with a central bore 17 which extends completely through the part 12. Threaded into the outer end of the bore 17 is a plug 18 equipped with a screw driver slot 19 and a stud 20. Threaded onto the outer end of the hub 16 is a readily removable cap 21, the function of which will be more fully described hereinafter.
- 15 20 The part 12 is equipped with a ring-like depression or seat 25 in which is seated a pressure plate 26 provided with a centrally disposed stud 27 which projects into the bore 17 and is in alignment with the stud 20 of the plug 18. The side of the backing plate 26 opposite that of the stud 27 formed thereon, is contiguous with the diaphragm 13.

Positioned in the bore 17 intermediate the plug 18 and the plate 26 and surrounding the studs 20 and 27, is a compression spring 28. Obviously, by removing the cap 21 and turning the plug 18, the pressure of the compression spring 28 exerted on the plate 26 and the contiguous diaphragm 13 may be varied.

40 The part 11 is provided with a passageway 29 into the outer end of which is threaded an inlet pipe 30 which may be connected to the usual receiver (not shown) in the conventional manner. The part 11 is provided with another passageway 32 which communicates at its inner end with the interior or space 33 of the part 11, and 45 at its outer end with an outlet pipe 34 threaded therein. The outlet pipe may be connected in the usual or conventional way to an expansion coil or chamber as the case may be (not shown).

50 Positioned inside of the part 11 in the space 33 and secured to the inner wall of the part 11 by bolts 35 (Fig. 1), is a bracket-like member 36 equipped with a pair of arms 37. Located intermediate the free ends of the arms 37 is a lever 38 pivoted thereto in any suitable manner by a pin 39.

Passing through one end 40 of the lever or arm 38 is a member 41 equipped with a threaded portion 42 threaded into the end 40. The member 41 is provided with a button head 43 and a shank 44, the end of which acts as a stop for preventing the diaphragm from being over-deflected, as will be more fully described hereinafter. It should be noted however, that the end of the shank

portion 44 is spaced from the interior wall of the part 11 (Fig. 2) when the diaphragm 13 is in its undeflected position.

Located intermediate the end 40 and the interior wall of the part 11 is a spring 45 which surrounds the shank 44 and a portion of the threaded part 42. Threaded onto the portion 42 in front of the end 40 of the lever 38, is a lock nut 46, the function of which will be more fully described hereinafter.

75 The other end 50 of the lever 38 is forked and straddles the flat end (Fig. 1) 51 of a needle valve member 52, the needle valve being designated generally by reference numeral 53'. The other end 53 of the member 52 projects into an opening 54 in a seat plug 55 threaded into the passageway 29. The end 53 is pointed and is shown in Fig. 2 as being seated in a pin-like aperture 56 in the seat plug 55. The pin-like aperture communicates with the inlet 30 through the means of a countersunk bore 57 in the end of the plug 55. The member 52 and the seat plug 55 comprise the members of the heretofore mentioned needle valve 53'. The plug 55 is provided with a small annular groove 59 into which a small amount of litharge is placed prior to screwing the plug in place.

85 90 Interposed between the inner end of the seat plug 55 and the end of the inlet pipe 30 in the passageway 29, is a screen 58. The screen 58 is cup shaped and fits into a pocket formed in the boss to which the pipe 30 is connected. The screen is filled with a packing of glass wool which filters the incoming fluid and takes out any particles of dust, scale, etc., which might be contained in the system and which might get under the valve 53'. The screen 58 and its packing may be removed when the pipe 30 is disconnected. Glass wool makes a good filter and is not attacked by the usual refrigerants such as sulfur dioxide, ammonia, etc. Any other suitable material might be used. The purpose of this screen 58 and its packing of glass wool is simply to protect the needle valve and its seat from foreign matter. This screen 58 is preferably a 100 105 110 small thimble type screen.

115 The operation of the improved expansion valve is as follows:—

The needle valve 53', as shown in Fig. 2, is in a closed position. That is to say, no liquid refrigerant is entering the space 33 of the expansion valve from the inlet 30. In order for this condition to exist, the pressure of the refrigerant in the expansion valve itself, the outlet 34 and the expansion coil (not shown) must be equal to or greater than a predetermined amount.

120 125 130 The compression spring 28 is much stronger than the spring 45. It is adjusted through the medium of the plug 18, as previously pointed out, to exert a pressure on the dia-

phragm 13 through the medium of the plate 26 slightly less than the predetermined amount of pressure mentioned above. When the pressure of the refrigerant in the 5 expansion valve, the outlet, and in the expansion coil, is below the predetermined amount, the total pressure on the diaphragm, by the fluid in the valve and coil, is slightly less than that exerted on the opposite side 10 of the diaphragm by the large spring 28. Consequently, the diaphragm is deflected in the direction of the low pressure, thereby, through the button head member 41, compressing the weaker spring 45. The 15 deflection of the diaphragm is limited by the shank portion of the stud 41 coming into contact with the inner wall of the casing. This movement of the member 41 causes 20 the valve member 52 through the lever 38 to be unseated, thereby opening the needle valve and permitting the fluid to flow. The screen 58, as stated before, prevents any 25 impurities from getting to the needle valve. The pressure plate 26 serves to prevent the spring 28 from injuring the diaphragm 13.

When sufficient refrigerant has entered the outlet 34 and expansion coil (not shown) to increase the pressure to the previously 30 mentioned predetermined amount, the reverse action takes place closing the needle valve. That is to say, the pressure of the liquid within the casing of the valve and the 35 cock, is then sufficient to move the diaphragm back to its undeflected position, overcoming the pressure exerted by the spring 28. The liquid in the expansion valve has a sufficient pressure to maintain 40 the diaphragm in its undeflected position. As soon, however, as the pressure of the liquid falls below the predetermined amount, the needle valve 53' is again closed.

In order to illustrate the foregoing more 45 clearly, let us assume that the adjustable plug 18 is set to give the spring 28 a pressure of one pound. When the pressure in the outlet 34 is slightly below one pound, the total pressure on the diaphragm 13 is slightly less than that exerted on the opposite side of the diaphragm by the spring 28. Consequently, the diaphragm deflects 50 in the direction of the lower pressure. The head of the member 41 being in contact with the diaphragm, also moves, causing the needle valve 53 to open and allowing the liquid to flow. When sufficient refrigerant 55 has entered the expansion valve outlet 34 and the expansion coil (not shown) to increase the pressure to one pound, the reverse action takes place which closes the needle valve. My expansion valve, in other words, 60 is in reality a form of a balanced pressure regulating or controlling device.

In assembling my valve, it is preferable 65 that a slight clearance be allowed between the diaphragm 13 and the button head 43,

so as not to hold the needle valve 53' open when the diaphragm 13 is in a neutral position. I find that a clearance of .010 inches adequately serves this purpose. This feature facilitates the manufacturing of the 70 valve and enables the ready replacement of parts in the valve when it is in operation, as well as to permit it to be easily and readily adjusted to the necessary clearance.

The removable seat plug 55 is also an 75 ideal construction, since it enables it to be readily replaced or removed from its threaded bore. Then, too, by applying litharge to the small annular groove 59 before screwing the plug 55 into place, I eliminate the necessity of employing a gasket. The litharge 80 forms a seal tight connection between the plug and the inner walls of the casing.

The lock nut 46 serves to limit the movement of the member 41. By loosening this 85 nut and turning the button head 43, the pressure of the spring 45 may be varied.

Now the cap 21 serves to prevent the moisture and condensation in the vicinity of the expansion valve from entering the spring 90 bore 17. Without this cap, moisture and condensation will seep into the seat of the pressure plate 26. It should be remembered that the expansion valve is usually employed 95 in an atmosphere in which the temperature quite frequently drops below 32 degrees F. or the freezing point. It is evident, therefore, that any moisture and condensation which might get into the seat of the pressure plate would freeze, causing the valve 100 to be inoperative in the off direction. Cap 21, as stated, obviates this possibility.

From the foregoing, it will be apparent 105 that the parts subject to service, may be easily and quickly removed from the expansion valve and replaced. This is particularly true of the members comprising the needle valve 53, namely, the valve member 52 and the plug seat 55. Then, too, my improved expansion valve above 110 described, is believed to function far more efficiently and quickly than the average type of valve of this character in existence at the present time.

I desire it understood, however, that my 115 invention is not to be limited by the foregoing description of what I deem the preferred embodiment of my invention, but only in so far as defined by the scope and spirit 120 of the appended claims.

I claim:—

1. In combination, a casing, an inlet to the casing, an outlet to the casing, the said inlet being connected to a fluid supply, a valve seat associated with the inlet, a needle valve member within the casing adapted to be seated in the said seat to prevent the flow of fluid into the casing, the said valve member and seat comprising a valve, the said valve being closed by the fluid within the cas- 130

- ing when the pressure thereof exceeds a pre-determined amount, and means for causing the valve member to become unseated, thereby opening the valve when the pressure of the fluid within the casing drops below the predetermined amount, comprising a member having a button head formed on one end which rests against the diaphragm, a lever pivoted intermediate its ends to the inside 10 wall of the casing, one end of which lever is adjustably connected to the button head member and whose other end is connected to the valve member, resilient means surrounding the other end of the button head member and disposed intermediate the end of the lever connected to the member and the wall of the casing, the said end of the button head member serving as a stop to limit the movement of the member and diaphragm, and 15 means disposed wholly within the casing for adjusting the tension of the resilient means associated with the button head member.
2. In combination, a casing, an inlet to the casing, an outlet to the casing, said inlet being connected to a fluid supply, a seat plug 20 threaded from the inside of the casing into the inlet, the said plug having a head abutting the inner wall of the casing and provided with a groove for receiving a sealing substance, the said head being tightly clamped to the inner wall of the casing to maintain the sealing substance in position intermediate it and the casing wall so as to pre-
- vent leakage into the casing from the inlet around the threads on the plug, a valve member within the casing adapted to be seated in the seat afforded by the plug to prevent the flow of fluid into the casing, the said valve member and plug seat comprising a valve, said valve being closed by the fluid 35 within the casing when the pressure thereof exceeds a predetermined amount, and means for causing the valve member to become unseated, thereby opening the valve when the pressure of the fluid within the casing drops 40 below a predetermined amount.
3. In a valve of the class described, the combination of a casing having an inlet, an actuating element, a needle valve controlling said inlet, a pivoted lever connected to operate the needle valve; and means adjustably connecting said lever with said actuating means, said connecting means acting as a stop for said actuating means.
4. In a valve of the class described, the combination of a casing having an inlet, an actuating diaphragm, a backing member for said diaphragm, a needle valve controlling said inlet, a pivoted lever having pivotal connection with the needle valve, and means 50 adjustably connecting said lever with said diaphragm, said connecting means acting as a stop for said actuating diaphragm.

In witness whereof, I hereunto subscribe my name this 30 day of April, 1925.

WILLIAM E. BIHL.
